Madam, ^{by} *Henry Lawrence.*

United States Patent Office.

THOMAS GRIFFIN, OF ROXBURY, MASSACHUSETTS.

Letters Patent No. 65,904, dated June 18, 1867.

IMPROVED FLOOR-CLOTH.

The Schedule referred to in these Letters Patent and making part of the same.

TO ALL WHOM IT MAY CONCERN:

Be it known that I, THOMAS GRIFFIN, of Roxbury, in the county of Norfolk, and State of Massachusetts, have invented a new and improved Floor-Cloth; and I do hereby declare that the following is a full, clear, and exact description thereof, reference being had to the accompanying drawings, making a part of this specification, in which—

Figure 1 is a view of one side of my improved floor-cloth.

Figure 2 is designed to represent a section through a floor-cloth which is printed on both sides so as to be reversible.

Similar letters of reference indicate corresponding parts in both figures.

The manufacture of floor-cloth which is printed in oil colors is attended with considerable manual labor, and requires the most experienced workmen to print the different-colored patterns and have them all in proper order. The canvas which forms the body of the cloth is first sized and then painted on both sides, so as to fill up the interstices and to leave the proper groundwork for the print. The pattern is then printed and the colors laid upon the cloth by means of blocks or types, representing different figures, colors, and patterns required to produce a given design. The object of my invention is to produce printed floor-cloth by a cheaper and less laborious operation than that above explained, for which purpose the nature of my invention consists in the application to paper of suitable thickness, of calico, or other woven fabric, which latter is cemented upon one or both sides of the paper, and caused to adhere firmly thereto, after which it is strengthened and rendered water-proof by covering its surface with a suitable oil or varnish, as will be hereinafter described.

The following is a description of one mode of carrying my invention into effect: I take a sheet of pasteboard of proper thickness, size, and strength, and firmly cement on both sides of it a woven fabric, such as calico, upon which is printed the required figure or design in water colors in the usual manner of printing such fabrics. When the floor-cloth thus produced becomes quite dry its surfaces are covered with oil or a suitable varnish, which will render the colors of the calico brilliant and fix them, and also render the cloth durable and impervious to the action of water. The floor-cloth is thus composed of paper, which will give body to it and render it strong and properly stiff, and cotton cloth, which will cover and protect the surfaces of the paper, and upon which the desired print or pattern can be formed previously to applying it to the paper, or, if desirable, after it has been so applied.

In carrying out my invention, I prefer to have both sides of the paper *a*, covered with printed cloth of different patterns, so that when one side of the floor-cloth becomes considerably worn the other side can be used by simply turning the cloth over. But one side of the paper only may be covered, if desirable, with printed cloth, the other side being covered with plain or unprinted cloth merely as a protection to the paper.

By my invention I am enabled to produce printed floor-cloths which will be very durable, and which will present the same appearance as the more expensive floor-cloths that are printed in oil colors by manual labor. The covering for the paper can be printed with any desirable pattern in the well-known manner of printing calicos and other cloths, and this fabric can be applied to the rolls of paper by means of machinery suitably adapted to the purpose. I am aware that paper stock and manufactured paper have been placed upon woven fabrics, so that the fabric has occupied a place intermediate or between two layers of paper. I also am aware that common plain paper made water-proof has been covered with figured wall-paper or painted; but I am not aware that in any instance the woven fabric has been exposed so as to become the wearing surface of the imitation oil-cloth or floor covering. My invention presents the woven fabric on both sides of the paper, and this woven surface or surfaces, as well as the edges thereof, together with the edges of the paper, is rendered water-proof in the manner described.

What I claim as my invention, and desire to secure by Letters Patent, is—

A floor covering or imitation oil-cloth, made substantially as herein described.

THOMAS GRIFFIN.
